DESCRIPTION

FIG. 1 is a front perspective view of a magnetic golf towel in accordance with the new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof;

The broken lines shown in FIGS. 1-7 depict environment that forms no part of the claimed design.

1 Claim, 5 Drawing Sheets
